US00D716879S

(12) **United States Design Patent**
Norman et al.

(10) **Patent No.:** US D716,879 S
(45) **Date of Patent:** ** Nov. 4, 2014

(54) **BEAM COMPONENT FOR A CONSTRUCTION KIT**

(71) Applicant: **Innovation First, Inc.**, Greenville, TX (US)

(72) Inventors: **David Anthony Norman**, Greenville, TX (US); **Robert H. Milmitch, III**, Rowlett, TX (US); **Paul David Copioli**, Rockwall, TX (US); **Gregory James Lavender**, Rockwall, TX (US); **Aren Calder Hill**, Rockford, IL (US); **Douglas Michael Galletti**, Allen, TX (US); **John Edward Vielkind-Neun**, Rockwall, TX (US); **Arthur Philip Dutra, IV**, Greenville, TX (US)

(73) Assignee: **Innovation First, Inc.**, Greenville, TX (US)

(**) Term: **14 Years**

(21) Appl. No.: **29/483,057**

(22) Filed: **Feb. 25, 2014**

(57) **CLAIM**

The ornamental design for a beam component for a construction kit, as shown and described.

DESCRIPTION

FIG. 1 is a front perspective view of a beam component for a construction kit in accordance with a second embodiment;

FIG. 2 is a rear perspective view of FIG. 1;

FIG. 3 is a top side view of FIG. 2;

FIG. 4 is a bottom side view of FIG. 3;

FIG. 5 is a right side view of FIG. 4;

FIG. 6 is a left side view of FIG. 5;

FIG. 7 is a front side view of FIG. 6; and,

FIG. 8 is a rear side view of FIG. 7.

The dash-dot broken lines represent the bounds of the claim and all other broken lines represent the environment in which the article resides. None of the broken lines form a part of the claimed design.

1 Claim, 8 Drawing Sheets
